CABINET DOOR HANDLE

Anthony R. Costantini, 860 Thomas Road, Lafayette Hill, Pa., and Anthony Di Angelus, 1735 Westchester Pike, Manoa, Pa.

Filed Nov. 21, 1963, Ser. No. 77,524

Term of patent 14 years

(Cl. D10—8)

We claim:

The ornamental design for a cabinet door handle, as shown.
